UNITED STATES PATENT OFFICE.

HARRY ALPHONSE WIDMER, OF LONDON, ENGLAND, ASSIGNOR OF ONE-HALF TO
A. LEWIS (FINSBURY) LIMITED, OF LONDON, ENGLAND, A COMPANY OF GREAT
BRITAIN.

FASTENER.

Application filed October 9, 1926, Serial No. 140,659, and in Great Britain September 24, 1926.

The present invention relates to fastening devices and its object is to provide a cheap and convenient adjustable fastening for straps of all kinds.

5 Two applications of the invention are illustrated by way of example in the accompanying drawings, in which:

Figure 1 is a plan view of the device applied to a shoe fastening,

10 Figure 2 is a perspective view of the device applied to a wrist watch strap, and

Figure 3 is a longitudinal section through the tab part of the fastener.

Referring to Figure 1 a bridge member 1 is secured upon a short flap 2 at the side of the shoe, while a tab member 3 described more fully below, is mounted on the strap 4 which passes over the instep. To adjust the strap a portion 5 passes through a loop 6 on the tab 3 and then back and in and out of transverse slits 7 in the body of the strap which slits are wider than the bent back portion of the strap end so that flat surfaces of the strap the full width of the strap end 20 lie in contact with said end which is retained in position by friction when the adjusted strap is in use on the member on which it is fastened. The portion 5 is shown set at its shortest. Naturally any number 25 of straps and fasteners may be used on the shoe.

In Figure 2 the same device is shown applied to a wrist watch, the length adjustment

being effected as shown in Figure 1 by a portion 5 passing through a loop 6 in the tab 3 and in and out of slits 7 in the body of the strap.

The tab fastening is illustrated in Figure 3 and comprises a recess tab piece 8 carrying the loop 6 and having pivoted thereon at 9 a metal shoulder 10. This shoulder is urged upward by a spring 11 held in place by the pivot 9 and is limited in upward movement by a stop 7 which engages the edge of the recess. In use the tab is pushed through the bridge 1 when the shoulder 10 is depressed. When fully home the shoulder springs up and prevents the tab from slipping back until the shoulder is deliberately depressed.

What I claim is:—

In a fastening for straps, shoes and the like, a loop in one member thereof, a strap end adapted to be adjusted passing through said loop and then bent back and passing in and out of a series of transverse slits in the body of the strap wider than the bent back portion of the strap end so that flat surfaces of the strap the full width of the strap end lie in contact with said end which is retained in position by friction when the strap is in use on the member on which it is fastened.

In testimony whereof I have signed my name to this specification.

HARRY ALPHONSE WIDMER.
